Walter G. Burns INVENTOR

UNITED STATES PATENT OFFICE.

WALTER G. BURNS, OF FORT WAYNE, INDIANA.

DISHWASHER.

Application filed August 4, 1919. Serial No. 315,119.

To all whom it may concern:

Be it known that I, WALTER G. BURNS, a citizen of the United States of America, and resident of Fort Wayne, in the county of 5 Allen and State of Indiana, have invented certain new and useful Improvements in Dishwashers, of which the following is a specification.

This invention relates to improvements in 10 dish washers and the objects thereof are: First, to provide a machine by means of which dishes, culinary and other similar articles may be cleansed and also dried without danger of breakage, and which may be 15 easily operated and which requires no handling of the articles during the washing and drying operations; and, second, to provide in a washing and drying machine of 20 its class an agitator so constructed and operated in a manner which will maintain, within the housing containing the articles, an exceedingly rapid air circulation and which will also cause washing liquid contained in the lower part of the housing to 25 pass in a fine spray into the circulating air to be carried thereby amongst the articles to be washed.

In some former devices agitators have 30 been arranged within a housing which throw quantities of washing liquid bodily over the dishes from which the liquid passes by the force of gravity to the lower part of the housing containing the agitator, the action of the agitator and the consequent 35 movement of liquid over the dishes being necessarily gentle because of liability of breaking the dishes. The intent in the present invention is to cause a rapid movement, amongst the articles to be washed, of air charged with washing liquid in a fine spray 40 so that even fragile articles such as dishes and light glassware may be subjected to forceful application of the cleansing agent without danger of breakage.

Another object is to so construct the machine 45 that the housing when open will afford ready accessibility to its washing chamber for convenience in placing and removing the articles to be washed therein; and also to so construct and arrange the operating parts of the machine and their controlling members as to afford convenience and simplicity in operation. And a further 50 object is to provide in connection with the housing an expedient for effecting the re-

turn thereinto of any liquid that may leak from its closure member.

The objects of the improvements are accomplished by the construction illustrated in the accompanying drawings in which:— 60

Fig. 1 is a perspective view of the machine in open position with the dish-rack and tray omitted;

Fig. 2 is a vertical central section in a plane extending from the front to the back 65 of the machine, parts thereof being shown broken away;

Fig. 3 is a horizontal section on the line $\alpha-\alpha$ of Fig. 2;

Fig. 4 is a detail view in section on the line $y-y$ of Fig. 3 showing the construction 70 of the overflow and drain tube and its actuating mechanism;

Fig. 5 is a detail view in section on the line $z-z$ of Fig. 3 showing the valve controlled water supply inlet; 75

Fig. 6 is a detail view showing a cross section of a slat, supporting pin and cross rod used in the construction of the dish-rack; 80

Fig. 7 is a perspective view of the agitator;

Fig. 8 is a perspective view of the dish-rack; and

Fig. 9 is a similar view of the dish-tray. 85

Similar characters of reference indicate corresponding parts throughout the several views and having reference now to the same:

1 is a basin having an upwardly extending flange 2 around its top, and a depression 3 formed in its bottom. In the front of the basin is a chute 4 formed for the reception of fluid. At each corner of the basin upon the exterior thereof is a threaded lug 5 into 90 which is secured a leg 6 formed of a suitable length of pipe upon which the basin is supported.

Upon the basin is secured a housing 7, its lower edges fitting within the flange 2 of the basin and being secured thereto in any suitable manner. The open front of the housing recedes toward its top and is provided with a closure member 8 having a handle 8' and which is hinged at the upper front edge 100 of the housing as indicated by 9, so that when in open position the top 10 of the closure member may rest upon the top 11 of the housing proper.

The sides 12 of the closure member are 110

triangular in form and the top 10 is of corresponding depth so that when the housing is closed it presents a cubical appearance. The closure member has a projecting lip 13 along its top and sides that extends within the housing when closed, and serves to prevent the escape of fluid at the junction between the housing and the closure member, and the housing 7 has an external lip 14 that projects forwardly from its sides 15 and the upper edge of its front 16, which is adapted to receive liquid that may escape from between the housing and its closure member and direct its return toward the basin. In the lower part of the housing is arranged a removable grid 17 which is supported at its edges upon an angle-iron frame 18 that is attached to the walls of the housing, there being a space 19 between the basin and the grid within the housing which serves as a fan-chamber. Along the front of the frame 18 is secured a pendant apron 16' that extends within the housing in a plane parallel with the front 16 thereof, there being a space 20 between the apron and the front for the passage of liquid from the lip 14, and the interior of the closure 8, in its return to the basin. Within the washing chamber 21 of the housing, is a ledge 22 for the support of a removable tray 23, the ledge being located so that the tray will be held a suitable distance above the dish-rack 24 which rests upon the grid 17. A water supply pipe 25 extends tightly through the bottom of the basin 1 and has upon its upper end a return joint 26 for directing the inflow of water from the pipe downwardly as it enters the basin, and the pipe has also a valve 27 beneath the basin for controlling the supply of water thereto. The basin has also a drain-pipe 28 the upper end of which is flush with its depression 3 and has an internal annular flange 29 at its top which acts as a valve seat. A drain tube 30 which is open throughout its length extends movably through the flange into the drain-pipe and has at its lower end an external flange 31 upon which rests a leather washer 32 that bears against the lower face of the flange 29 when the tube is in its uppermost position and acts as a valve to prevent the direct flow of liquid from the basin into the drain-pipe. The tube when held in its uppermost position acts as an overflow outlet for excess liquid in the basin when it reaches the level at the top of the tube, and when in lowermost position the tube serves as a discharge outlet so that the basin may be emptied of its liquid content therethrough into the drain-pipe. Thus the basin retains a quantity of liquid or becomes emptied accordingly as the tube is positioned. Movement of the tube is effected through the medium of a

pivoted bell-crank 33 which has connection with the tube at its lower end by means of a rod 34 that extends through the tube, there being also an operating rod 35 attached to the bell-crank, that extends through the front of the housing with a knob 36 on its projecting end. A tension spring 37 is secured at one end to an anchor pin 38 on the basin and has connection at its other end with a pin 39 on a bell-crank 75 which is located thereon at a point to one side of the pivotal support 40 of the latter, opposite the anchor pin, and the spring is so arranged that its line of tension lies in a plane above the center of the pivotal support when the tube is at its uppermost position and below that center when the tube is at its lowermost position. Thus, the tube is held inert in either of its opposite positions according to which it is adjusted.

Attached to the under side of the basin is an electric motor 41 which has an extending bearing 42 that projects upwardly through the basin into the fan-chamber, in which the motor shaft 43 rotates. The motor is located beneath the depression 3 and the bearing 42 fits tightly in the opening in the basin through which it extends so that leakage of liquid from the basin onto the motor is avoided. Upon the upper end of the motor shaft 43 is secured an agitator comprised of two distinct members, viz: a fan 44 and an impeller 45, the latter being clamped in place between the hub 46 of the fan and a block 47, there being a number of rivets 48 which rigidly secure the parts together. An axial opening 49 extends through the agitator for the reception of the motor shaft. The fan may be of any suitable form adapted to cause a rapid circulation of the atmosphere in the housing when rotated, and is located in the fan-chamber in a plane suitably distant above the overflow level of liquid in the basin. The impeller 45 is comprised of pendant blades 50 arranged respectively on opposite sides of the axis of rotation and with their lower extremities extending below the overflow level of liquid in the basin and into the depression therein. The rear edge of each blade has an outwardly curved lip 51, slantingly disposed so that as the agitator is rotated the liquid in the basin that is engaged by the impeller will become thrown thereby in fine sprays into the fan-chamber from which it is drawn by the suction of the fan and forced through the grid into the washing chamber together with the rapidly circulating air within the housing.

A conduit 52 having a switch 53 at one end and a terminal box 54 at the other is secured beneath the basin and serves to shelter the electrical conductors (not shown) for the motor. The switch 53, water sup.

ply valve 27, the knob 36 on the operating rod, the chute 4 of the basin, and the handle 8' on the closure are all located at the front for the convenience of the operator in manipulating the machine.

The dish-rack 24 is comprised of a rectangular frame 54 having opposite hand-holds 55 in its sides and ends, and within the frame at the bottom thereof are secured 10 a series of slats 56 having tapering lower edges, each slat having a series of upwardly projecting posts 57, the slats being spaced apart to admit upward and downward passage of fluid therebetween. Also a series 15 of cross rods 58 extend from one side of the frame through the slats 56 to the opposite side thereof which serve to hold the slats from tilting and prevent articles contained in the rack from falling between the 20 slats. The posts serve to prop dishes and similar articles in an edgewise position so that they do not unnecessarily obstruct the circulation of fluid in its passage into and from the washing chamber.

25 The tray 23 is comprised of a rectangular frame 59 having opposite hand-holds 60 in its sides and ends, and within the frame are secured vertical partitions 61 that are spaced apart and extend from one end of 30 the frame to the other. Between each partition and the adjacent side of the frame and also between said partitions are secured corresponding screens 62 slantingly disposed and adapted to support thereupon 35 articles of various kinds to be washed. The dish-rack and the tray are each made with similar length and breadth so that they may be inserted into the washing chamber lengthwise or sidewise as desired. Both 40 the rack and the tray are constructed so as to admit of the upward and downward passage of fluid therethrough with no more hindrance than is necessarily occasioned by the supports for the articles placed therein.

45 The grid serves as a guard for the fan as well as a support for the dish-rack.

The machine herein disclosed in detail is merely an example of the invention as applied to domestic or household use, and this 50 may be modified in the construction and arrangement of its various parts without departure from the spirit of the invention. The invention is also applicable for various and more pretentious washing and drying 55 operations, such as are required in restaurants, hostelleries, soda and ice-cream dispensaries, etc., in which instances suitable modifications of the example disclosed may readily be made by the skilled mechanician 60 to suit the invention to needs peculiar to the requirements.

In operating the invention the rack is placed in the housing upon the grid with the dishes placed edgewise amongst the 65 posts, and the tray is placed upon the ledge

22 with articles to be washed laid upon the slanting screens 62 in tilted positions so that liquid will readily drain from any concavities they may have. Such articles as spoons, cups, tumblers, glasses and other 70 hollow articles are placed in the tray or in the rack in such positions as to preclude their retaining liquid. The washing chamber is then closed by turning the closure member downwardly. Steaming hot water 75 is then introduced into the basin through the valve 27 which is intended for connection with a suitable source of steam or hot water. Or, water may be heated in a vessel (not shown) apart from the machine 80 and introduced into the basin through its chute 4. The water is retained in the basin by the tube 30 which is adjusted to its uppermost position by pushing the rod 35 inwardly. Should the water supplied to 85 the basin rise to a level above the top of the tube, the excess overflows therethrough into the drain-pipe. The motor is then set in motion by turning the switch and the agitator thereupon revolves rapidly 90 causing the atmosphere within the fan-chamber to move forcefully upward through the grid, rack and tray, and amongst the articles contained in the washing chamber. A corresponding downward movement of 95 air from the washing chamber into the fan chamber is occasioned by the rising flow, and because of the suction of the fan. The liquid in the basin is raised, by the action of the impeller, in sprays, into the suction area in the fan-chamber and is drawn up therefrom together with the contained air and forced by the action of the fan through the grid into the washing chamber and amongst the articles contained in the rack 100 and tray with cleansing effect. Thus, the contained articles are subjected to the abrasive action of the heated and forcefully circulated wet air. Soap or substances of similar nature may be utilized in the washing process by placing such substances exposed within the housing or basin so that the washing fluid becomes charged therewith. When the washing process above described has progressed sufficiently to insure 115 thorough cleansing of the articles, the tube 30 is adjusted to its lowermost position by pulling out the operating rod 35 so that the liquid content of the housing and basin will gravitate through the tube into the 120 drain-pipe. The tube is then readjusted to its former position and the basin is charged with clear hot water, which results in a thorough rinsing of the articles previously washed, after which the tube is returned to 125 its lowermost position and the rinsing liquid expelled as in the former instance.

The articles thus treated to the washing and rinsing operations are then dried by subjecting them while hot, to a blast of air 130

from the fan while the closure member is raised to open position.

During the foregoing washing and rinsing operations the liquid raised by the impeller is broken into fine spray by the fan which rotates at an exceedingly high velocity, and is carried with the contained air that is rapidly circulated within the housing by the action of the fan. Thus, the cleansing agent is forcefully applied uniformly to the entire surfaces of the articles contained in the rack and tray without disturbing their positions so that breakage is thereby avoided.

What I claim is:—

1. In a dish washer, a housing having a washing chamber and also means at its base adapted to contain liquid; a fan operable above the level of liquid for causing circulation of the air within the housing; and means for raising the liquid into the air thus circulated.

2. In a dish washer, a housing including means at its base for holding liquid, a fan operable above the level of liquid therein; and an impeller extending into the liquid adapted to force it into the suction area of the fan.

3. In a dish washer, a housing for inclosing articles therein to be washed and having means in its base adapted to contain a quantity of washing fluid; means for creating rapid circulation of air within the housing; and means for infusing the contained fluid into the circulated air.

4. In a dish washer having a housing for enclosing articles therein to be washed and being adapted to contain in its base a limited quantity of liquid, means for raising particles of the liquid into the contained air; and means for breaking the liquid thus raised into fine spray and for creating rapid circulation of the contained air.

5. In apparatus of the class described including a housing for enclosing articles to be washed therein having means at its base for containing a limited quantity of liquid, and a closure member at its upper part, a horizontally disposed grid arranged in the housing separating the housing into a washing chamber and a fan-chamber; means for

supporting articles to be washed removably positioned in the washing chamber; means within the fan-chamber for causing circulation of air between the fan-chamber and washing chamber through the grid; and means for raising particles of the contained liquid into the air thus circulated.

6. In apparatus of the class described, a housing having an open forward part that recedes from its front toward its top and is provided with a projecting lip extending along the sides and bottom of the opening; a horizontal frame arranged within the housing at a point approximately at the bottom of the opening; a grid removably positioned in the frame separating the lower from the upper portion of the housing; a hollow closure member hinged to the top of the housing, its sides and lower front edge extending within the lip when in closed position; an apron extending from the front of the frame downwardly adjacent the front of the housing, there being a space between the apron and the front for the downward passage of liquid from the lip and the closure member; and means to spray water in the upper portion of the housing.

7. In a washing machine having a housing with an opening therein and closure therefor and also means at its base for containing a limited quantity of liquid, a grid horizontally disposed within the housing approximately at the bottom of the opening therein dividing the housing into two chambers; a removable dish-rack supported by the grid and being so constructed as to admit upward and downward passage therethrough of fluid; and an agitator contained within the chamber beneath the grid adapted to cause rapid air circulation between the chambers through the grid and rack and to infuse the contained liquid into the air thus circulated.

In testimony whereof I affix my signature, in presence of two witnesses.

WALTER G. BURNS.
